UNITED STATES PATENT OFFICE.

RUDOLPH LIEBMAN, OF NEW YORK, N. Y.

DESIGN FOR A BUTTON.

SPECIFICATION forming part of Design No. 18,515, dated August 7, 1888.

Application filed June 16, 1888. Serial No. 277,380. Term of patent 3½ years.

To all whom it may concern:

Be it known that I, RUDOLPH LIEBMAN, a citizen of the United States, residing at New York, in the county and State of New York, have invented and produced a new and original Design for Buttons, of which the following is a specification, reference being had to the accompanying drawing, forming part thereof.

My invention consists in a new design for buttons, as fully set forth in the following specification and claim and illustrated in the accompanying drawing, which represents a face view of a button containing my design.

In the drawing, the letter A indicates the button, circular in outline and provided with a marginal bead. The face of the button constitutes a field, a, containing the representation or figure of an eagle, B, of a color contrasting with the color of the field. A diagonal panel, C, extends across the body of the eagle upon the field, and is of a color contrast-

ing with the color of the field and with the color of the eagle.

What I claim as new, and desire to secure by Letters Patent, is—

The design for a button, A, circular in outline and provided with a marginal bead, and having the field a, containing the eagle B, of a color contrasting with the color of the field, and the diagonal panel C, extending across the body of the eagle upon the field, and of a color contrasting with the color of the field and with the color of the eagle, substantially as shown and described.

In testimony whereof I have hereunto set my hand and seal in the presence of two subscribing witnesses.

RUDOLPH LIEBMAN. [L. S.]
